(57) **CLAIM**

The ornamental design for a full immersion therapy lounge, as shown and described.

DESCRIPTION

FIG. 1 is an upper rear right perspective view of a full immersion therapy lounge showing our new design in accordance with a first embodiment of the present invention; FIG. 2 is a front elevation view thereof; FIG. 3 is a rear elevation view thereof; FIG. 4 is a top view thereof; FIG. 5 is a right side elevation view thereof; FIG. 6 is a left side elevation view thereof; FIG. 7 is a cross-sectional view thereof taken along lines 7-7 shown in FIG. 4; FIG. 8 is an upper rear right perspective view of a full immersion therapy lounge showing our new design in accordance with a second embodiment of the present invention; FIG. 9 is an upper front left perspective view thereof; FIG. 10 is a front elevation view thereof; FIG. 11 is a rear elevation view thereof; FIG. 12 is a top view thereof; FIG. 13 is a right side elevation view thereof; and, FIG. 14 is a left side elevation view thereof. The portions of the full immersion therapy lounge shown in broken lines form no part of the claimed design. The dashed-dotted line showings of FIGS. 8, 9, 12, and 13 illustrate boundaries between the claimed design and environmental features.
